DESIGN FOR A NEGLIGEE

Violet Giovagnoni, New York, N. Y.

Application January 13, 1947, Serial No. 136,111

Term of patent 3½ years

(Cl. D3—26)

To all whom it may concern:

Be it known that I, Violet Giovagnoni, a citizen of the United States, residing in New York city, in the county of New York and State of New York, have invented a new, original, and ornamental Design for a Negligee, of which the following is a specification, reference being had to the accompanying drawing, forming part thereof.

Fig. 1 is a front view of a negligee showing my design,

Fig. 2 is the rear view thereof on a reduced scale, and

Fig. 3 is an enlarged fragmentary view of the negligee shown in Fig. 1 illustrating the sleeve trim detail.

The characteristic feature of my design resides in the specific negligee in combination with the sleeve ornamentation consisting of flowing, intercrossing musical lines, interspersed by cherubs, all as shown.

I claim:

The ornamental design for a negligee, substantially as shown and described.

VIOLET GIOVAGNONI.
